UNITED STATES PATENT OFFICE.

OZELLO R. HUNT, OF CHICAGO, ILLINOIS, ASSIGNOR TO THE SIMMONS MFG. CO., OF KENOSHA, WISCONSIN, A CORPORATION OF WISCONSIN.

MATTRESS AND BED SPRING.

1,013,294.

Specification of Letters Patent.

Patented Jan. 2, 1912.

Application filed July 26, 1910. Serial No. 573,905.

To all whom it may concern:

Be it known that I, OZELLO R. HUNT, a citizen of the United States, residing at Chicago, in the county of Cook and State of Illinois, have invented certain new and useful Improvements in Mattress and Bed Springs, of which the following is a specification.

This invention relates to improvements in mattress and bed springs, and refers more particularly to springs of that type in which a series of coiled springs are connected side by side over the area of the construction; the springs being generally hour-glass shaped.

Among the salient objects of the present invention are to provide a construction in which the springs are reliably united in such manner as to form in effect a continuous surface fabric yet nevertheless are capable of being folded or rolled up along any of the lines of juncture of the springs, either longitudinally or transversely of the construction; to provide a construction which is specially suitable for use inside of a double-faced mattress, by reason of its capability of bending and folding without injury, by reason of its extreme compressibility and by reason of the uniformly smooth surfaces provided for contact with the mattress both above and below; to provide a construction in which the spring units are so united as to provide perfect hinge connections with each other, yet the adjoined wires are so held as to be practically noiseless and practically incapable of displacement from their proper relations to each other; to provide a construction in which each end of each unit is spanned by a bridge wire which precludes the forcing of the smaller coils of the spring axially beyond their limits of elasticity, and therefore prevents the springs from becoming permanently distorted; to provide a construction in which the adjoining springs are provided with interfitting corresponding offsets and insets, the contacting parts of which are held in the same plane by clips, thereby affording a reliable hinge connection, absolutely locking the springs against radial or torsional displacement, and contributing toward noiselessness; and in general, to provide an improved construction of the character referred to.

55 The invention will be readily understood

from the following description, reference being had to the accompanying drawings, in which—

Figure 1 is a plan view of a section of springs showing the relative arrangement and manner in which they are connected; Fig. 2 is an edge elevation of the part shown in Fig. 1; the manner in which the springs may be flexed upon each other in folding up being shown in dotted lines; Fig. 3 is a detailed plan view of one of the springs and fragmentary portions of adjacent connected springs; Fig. 4 is a sectional view taken on line 4—4 of Fig. 3; Fig. 5 is a perspective view of one of the springs; Fig. 6 is an edge elevation of the spring shown in Fig. 4 compressed.

Describing the preferred embodiment of my invention shown in the drawings, the springs there shown are of the hour-glass type, the opposite sides of the spring structure being precisely identical, although it is obvious that the invention may be utilized, so far as one surface is concerned, when the springs are of cone-form.

Each spring 1 in the preferred construction shown has its large terminal coils, as 2, 2', provided with four abrupt bends, as 3, 3', 4 and 4', arranged in pairs at right angles to each other, *i. e.* at 90° apart. The bends 3, 3', are radially outset, as best seen in Fig. 3, while the bends 4, 4', are radially inset, and in connecting up the springs they are, with reference to these insets and outsets, arranged at right angles to each other; the outsets 3, 3', of one spring being arranged to fit within the corresponding insets 4, 4', of the adjacent springs. The adjacent internesting or interfitting portions of the contiguous springs are united and held in the same plane by suitable U-shaped clips 5; these clips being preferably formed of sheet metal and provided in the ends of the U-arms with registering apertures 6.

To hold the clips in their adjusted positions, *i. e.* embracing the interfitted parts of the springs, bridge wires 7 are provided; each spring being provided at each end with one such bridge wire, the ends of which are looped through both ears of each clip, as shown clearly in the drawings. As a feature of some importance in that it contributes to the noiselessness and reliability of operation of the structure, these bridge wires are of a length slightly less than suffi-

cient to reach from ear to ear of the clips when the coil which it bridges takes the circular form primarily given it, so that when the bridge wire is engaged with the clips the end coil of the spring is held under a distinct tension and made very slightly elliptic. The extremities of the bridge wires are bent back toward each other so as to hold the ends of the clips reliably against 10 spreading apart, and inasmuch as the space between the two arms of each clip is just sufficient to accommodate the thickness of the wires of the coils, it follows that at these hinge connections they are held reliably in the same plane.

Heretofore it has been customary to twist the extreme end of the wire which forms the outermost large coil of the spring around the next smaller coil to provide a 20 suitable finish for the end of the spring, but I prefer to save the expense of so doing, and at the same time provide a somewhat better construction, by making the end of the large coil terminate just beyond one of the inset 25 or offset portions thereof, as the case may be, so that the clip holds this end, and in order to connect the terminal coil to the next subjacent coil I provide an offset 8 in the spring at the point which marks the 30 juncture of the first and second coils; this offset 8 being so shaped as to be engaged by that part 7' of the bridge wire which passes through the eyes of the clip. Inasmuch as the space inside the clip is just sufficient to 35 accommodate the three wires embraced, it follows that the coils at the point 8 are thus perfectly and reliably united and that this union is accomplished by the same means which serves to tie together the contiguous 40 springs.

By reason of the fact that the bridge wires are individual to the several springs, *i. e.* they in no instance extend radially outside of the spring to which they pertain, it 45 follows that they do not in the slightest interfere with the folding up of the structure along any of the lines of connection between the springs. It is also obvious that these bridge wires,—one at each end of each 50 string,—serve to absolutely confine the smaller inner coils against telescoping through the outer terminal coils, and thus preclude the possibility of bending the coils together or past each other far enough to 55 give them a permanent set.

Inasmuch as the bridge wires are alternately arranged at right angles to each other in the successive springs of any given row, and inasmuch as the terminal coils of 60 the springs are capable of being distorted slightly, *i. e.* sprung out of their normal shape, in a direction at right angles to the bridge wires, it follows that the surface of the spring structure is slightly elastic; the 65 aggregate elasticity of a given row extend-

ing the full length or width of the bed being substantial. This is a feature of much importance when the spring structure is used inside or beneath a thin mattress, because each individual part of the spring 70 structure will yield to accommodate the body. The importance of making the bridge wires individual to the several springs should not be underestimated because this also contributes to the pliability 75 of the spring structure and yet does not seriously sacrifice its strength.

While I have herein shown and described what I deem to be the best embodiment of my invention, nevertheless modifications 80 may be made without departing from the spirit thereof. For example, it will be noted that the bends are not internested with corresponding bends in the adjacent wires yet they are nevertheless reliably confined by 85 the clips and bridge wires, and this at once suggests that it is not absolutely essential that the other wires be actually internested, *i. e.* bent in such manner as to interfit, in order that they be held reliably in proper 90 relation, although this is the preferred construction. Accordingly the claims hereto appended are to be construed broadly, except in so far as they are couched in specific terms.

I claim as my invention:

1. In a furniture spring structure, a series of coiled springs arranged side by side with their terminal large coils in juxtaposition, the peripheral portions of said terminal large 100 coils being provided with interfitting abrupt radial deflections or bends, whereby they are locked against circumferential movement relatively to each other, and tying devices embracing said interfitting portions, holding them in the same plane and holding them against radial separating movement.

2. In a furniture spring structure, a row of coiled springs arranged with their terminal large coils in juxtaposition, the peripheral juxtaposed portions of said terminal large coils being provided with closely fitting internesting bends lying in the plane of the surface of the spring structure, whereby said springs are locked against circumferential movement out of alinement 110 with each other in the row, clips embracing said internested peripheral portions and holding them in the same plane with each other, and bridge members extending diametrically across every alternate spring in the row and connecting the clips of that spring.

3. In a furniture spring structure, a set of coiled springs arranged in rows in two 125 directions at right angles to each other and with the peripheral portions of their large terminal coils in juxtaposition, the juxtaposed peripheral portions of said terminal large coils being provided with closely fit- 130

ting internested abrupt shoulders or bends, hinging devices embracing and tying together the juxtaposed shoulders or bends of contiguous springs, and a bridge member 5 extending diametrically across the terminal coil of each spring and tying its opposed sides together, the bridge members of alter-

nate springs in each row and in each direction being arranged at right angles to each other.
